ELECTRIC SWITCH

Ralph H. Kingdon, Detroit, Mich., assignor to
 Square D Company, Detroit, Mich., a corpora-
 tion of Michigan

Application February 27, 1941, Serial No. 380,841

13 Claims. (Cl. 200—67)

This invention relates to electric switches, and more particularly to manually operated electric switches in which the switching element is operated to its switching positions with a snap action.

One object of the invention is a manually operated electric switch with overcenter spring mechanism for actuating the switch to its operating positions with a snap action provided with means preventing the mechanism from having a dead center position.

Another object of the invention is to provide a manually operated electric switch having overcenter spring mechanisms for providing the switch with a snap action in which the only stable position of the operating mechanism will be the full "on" and full "off" positions of the switch.

Another object of the invention is to provide a manually operated electric switch having overcenter spring mechanism for operating the switch with a snap action in which the operating handle, unless manually held, will be maintained at all times either in the full "on" or full "off" position corresponding to the position of the switching mechanism.

In electric switches of the manually operated overcenter spring, snap-acting type, particularly in the rather heavy industrial switches utilizing knife blade and jaw contacts, it has been found that it is sometimes possible to place the parts in a dead center position in which they are semi-stable without being either in the true "on" or true "off" position. The parts of the operating mechanism of these switches are made to rather wide tolerances and it sometimes occurs that a rather broad dead center position results which is effective over a relatively wide arc of movement of the parts. In going from the "on" to the "off" position, it is possible for the parts to reach this semi-stable, dead center position while the contacts are still engaged and with the operating handle out of the "on" position. If the switch were left in this position, a casual inspection of the exterior would, from the position of the operating handle, indicate that the circuit was open through the switch, whereas in fact the circuit is still closed and a dangerous condition is thus produced if an attempt is made to work on the live circuit closed through the switch. On the other hand, in going from the "off" to the "on" position, this semi-stable dead center position of the parts might be reached with the contacts remaining separated and a subsequent jarring or other causes effect move-

ment of the parts from the semi-stable into the "on" position with closing of the circuit with possible dangerous results. The object of this invention is to avoid the occurrence of the semi-stable dead center position in manually operated electric switches using overcenter spring operating mechanisms so that both the switching parts and the operating handle will always be in full "on" or full "off" position; and, hence, it will be impossible to place the parts in any semi-stable intermediate position.

Other objects and features of the invention will be readily apparent to those skilled in the art from the specification and appended drawings illustrating certain preferred embodiments of the invention in which:

Figure 1 is a front elevational view of an electric switch according to the present invention with the front cover broken away to show internal parts.

Figure 2 is a vertical sectional view showing the operating mechanism for the switch.

Figure 3 is a partial horizontal sectional view of the operating mechanism.

Figure 4 is a vertical view similar to Figure 2 but with the parts in a different operating position.

Figure 5 is an enlarged view of an operating part of the mechanism.

Figure 6 is a view of the operating part of Figure 5 taken in the direction of the arrow VI.

Figure 7 is a view of the operating part of Figure 5 taken in the direction of the arrow VII.

Figure 8 is a view similar to Figure 5 but of a modified arrangement for the operating part.

The electric switch of the present invention comprises a sheet metal enclosing box 1 having an openable cover 2 hingedly mounted thereon. Within the box, the switching parts comprise stationary jaw contact members 3 and knife blades 4 hingedly mounted in jaws 5. Below the contacts are disposed pairs of fuse clips 6 and 7 for the inclusion in the circuit of circuit protecting fuses. The knife blades 4 are connected by means of straps 8 to a common insulating bar 9 which is, in turn, connected through the links 11 to an operating bail 12 pivotally mounted at one end in the left side wall of the box and pivoted at its other end as will be hereinafter described.

Upon the back wall of the box is secured an L-shaped bracket 13 provided with an opening which, in conjunction with an opening in the right hand side wall of the box, serves to pivot the operating handle 14, having an exterior grip-

ping portion 15 and an interior horizontal portion 16. Keyed upon the interior end of the operating handle for movement therewith is an operating finger 17 having a flat opening receiving the flattened end of the operating handle so as to be rigidly moved therewith, this keying being shown in Figures 2 and 4. Upon the horizontal portion 16 of the operating handle is rotatably mounted an element 18 shown more in detail in Figures 5, 6, and 7, the element 18 having keyed therewith a bushing 19 upon the exterior surface of which at the left hand side, as viewed in Figure 3, the end of the operating bail 12 is looped and pivotally mounted. The element 18 is provided with a pair of spaced integral lugs 21 and 22 between which are disposed both the finger 17 and the arm 23 of the bail 12.

Upon the right hand side wall of the box is pivotally mounted a guide bracket 24 having a slot therein through which extends a spring guide 25, about which is coiled the operating spring 26. The opposite end of the spring guide 25 is secured to the element 18 by means of a pin 27 connected to the guide and disposed in a slot 28 in the element 18. This slot is in the form of an obtuse angle and the pin 27 is adapted to slide therein. A second slot 29 is provided at the opposite end of the element 18 and this is to be used with a duplicate spring guide and overcenter spring in case a greater operating force is desired.

In the operation of the switch, it is seen that the placing of finger 17 between lugs 21 and 22 provides for a lost motion connection between the operating handle and element 18, and the placing of the arm 23 of bail 12 between the lugs 21 and 22 provides a second lost motion between the element 18 and the operating bail 12. As the handle is pulled downwardly from the position of Figure 1, finger 17 engages lug 22 to rotate element 18 in a clockwise direction, as viewed in Figure 2, against the force exerted by spring 26. The initial movement of the element 18 is effected without moving the bail 12, but after it has moved through a certain distance, the lug 21 engages the arm 23 of bail 12 and effects positive movement of the bail from the now positive connection with the operating handle in the clockwise direction. At this time, the blades 4 will start their movement out of contact jaws 3. Just prior to the time when the blades 4 leave the jaws 3, the spring 26 will snap overcenter and will thereupon apply its bias to continue the rotation of the element 18 in a clockwise direction, thus quickly snapping the blades 4 out of the jaws 3 and into their full "off" position with the parts being then related as shown in Figure 4.

With the invention herein disclosed, at a certain angle prior to the actual dead center line of spring 26, say, for example, at an angle of 10° to this dead center line, the angle of slot 28 with respect to the direction of force exerted on spring guide pin 27 becomes such as to effect movement of the pin within the slot so that spring 26 moves through its dead center position irrespective of further movement of the member 18 toward operating position. This occurs a sufficient distance prior to the actual dead center position and throws the spring a sufficient distance through the dead center position, so that it is impossible to effect a maintenance of the operating parts in dead center position. Furthermore, the sudden stopping of pin 27 in the slot after it has moved the spring through dead

center position provides a hammer blow which positively overcomes the remaining friction between the jaws 3 and blades 4 to ensure their proper separation.

The operation of the parts from the "off" position of Figure 4 to the "on" position of Figure 2 is just the reverse of that previously described, and in view of the obtuse angle formed by the slot 28, the pin 27 will again move within 10 the slot as the spring approaches its dead center position and will throw the spring through its dead center position so that the parts again will be positively moved to their "on" position without the possibility of retaining them in the dead center position.

In the modification of Figure 8, the element 18 is therein provided with a straight slot 31 adapted to receive the spring guide pin 27. In view of the straight line characteristic of this slot, the movement of the pin therein occurs only in one direction so that the movement of the spring through its dead center position irrespective of the movement of the element 18 occurs only in one direction. Such a slot could be used to operate in either direction but would normally be utilized to move the spring through dead center position in moving from "on" to "off" positions to ensure proper opening of the switch. However, the obtuse angle slot of the preferred embodiment is the preferred form of the invention as it provides for movement of the point of attachment of the spring in both directions of operation and, hence, prevents the maintaining of parts in a dead center position 35 in both directions of operation of the switch.

While certain preferred embodiments of the invention have been specifically disclosed, it is understood that the invention is not limited thereto, as many variations will be readily apparent to those skilled in the art and the invention is to be given its broadest possible interpretation within the terms of the following claims.

What is claimed is:

1. In an electric switch, cooperating stationary and movable contacts, an operating bail connected to the movable contacts, an operating handle, means interconnecting said handle and bail, said means including lost motion connections to both the handle and bail, an overcenter spring connecting to said interconnecting means, and means for effecting movement of the point of spring connection to the interconnecting means independent of movement of the interconnecting means when the overcenter spring has been moved to a predetermined position so as to effect movement of the overcenter spring through its dead center position independent of movement of the operating handle.

2. In an electric switch, cooperating stationary and movable contacts, operating means connected to the movable contacts, an operating handle, means interconnecting said handle and operating means, said interconnecting means including a lost motion connection to both the handle and operating means, an overcenter spring connected to said interconnecting means and movable through its dead center position to effect snap movement of the operating means, and means for effecting movement of the point of spring connection to said interconnecting means when the spring has been operated to a predetermined position, said movement throwing the spring through its dead center position independently of further movement of the parts and pre-

venting maintenance of the parts in a semi-stable, dead center position.

3. In an electric switch, cooperating stationary and movable contacts, operating means connected to the movable contacts, an operating handle, means interconnecting said handle and operating means, said interconnecting means including a lost motion connection to both the handle and operating means, an over-center spring operatively connected to said interconnecting means by a pin and slot connection and movable through its dead center position to effect snap movement of the operating means and movable contacts, said slot being so directed with respect to the line of action of said over-center spring as to effect movement of the pin within the slot when the spring has been operated to a predetermined position, said movement moving the spring through its dead center position independently of further movement of the operating handle preventing maintenance of the parts in semi-stable, dead center position.

4. In an electric switch, cooperating stationary and movable contacts, operating means connected to the movable contacts, an operating handle, means interconnecting said handle and operating means, said interconnecting means including a lost motion connection to both the handle and operating means, an overcenter spring operatively connected to said interconnecting means through a pin and slot connection, with the slot being in the form of an obtuse angle, the legs of the slot being so located with respect to the line of action of the over-center spring as to effect movement of the pin within the slot to throw the spring through its dead center position in both directions of movement as it approaches what would have been its dead center position without the pin and slot connection whereby the parts cannot be maintained in a semi-stable, dead center position.

5. In an electric switch, cooperating stationary and movable contacts, operating means connected to the movable contacts, an operating handle, means interconnecting said handle and operating means, said interconnecting means including a lost motion connection to at least the operating handle, a spring guide connected to said interconnecting means by a pin and slot connection at one end, guide means slidably receiving the other end of said spring guide, an overcenter spring mounted on said spring guide and movable through its dead center position to effect snap movement of the operating means and the movable contacts, said slot being so directed with respect to the line of action of the spring as to effect movement of the pin within the slot to move the spring through its dead center position independent of further movement of the operating handle when the spring has been moved to a predetermined position.

6. In an electric switch, cooperating stationary and movable contacts, operating means connected to the movable contacts, an operating handle, means interconnecting said handle and operating means, said interconnecting means including a lost motion connection to at least the operating handle, a spring guide connected to said interconnecting means by a pin and slot connection at one end, pivotally mounted guide means slidably receiving the other end of said spring guide, an overcenter spring mounted on said spring guide and movable through its dead center position to effect snap movement of the operating means and the movable contacts, said

slot being so directed with respect to the line of action of the spring as to effect movement of the pin within the slot to move the spring through its dead center position independent of further movement of the operating handle when the spring has been moved to a predetermined position.

7. In an electric switch, cooperating stationary and movable contacts, operating means connected to the movable contacts, an operating handle, means interconnecting said handle and operating means, said interconnecting means including a lost motion connection to at least said operating handle, a spring guide connected at one end of said interconnecting means through a pin and slot connection, guide means for the opposite end of said spring guide, an overcenter spring mounted on said spring guide and movable through its dead center position to effect snap movement of the operating means and movable contacts, said slot being in the form of an obtuse angle and serving to effect movement of the point of spring guide connection to the interconnecting means so as to throw the overcenter spring through its dead center position independent of further movement of the operating handle when the spring has been operated to predetermined positions in both directions of operation of the switch.

8. In an electric switch, cooperating stationary and movable contacts, an operating handle, means for effecting movement of the movable contact in response to movement of the operating handle, including an overcenter spring movable through its dead center position to effect snap movement of the movable contact, a pin and slot connection for one end of said overcenter spring, said slot being in the form of an obtuse angle, the legs of said angle being so related to the line of action of the overcenter spring as to effect movement of the spring through its dead center position independent of further movement of the operating handle when the spring has been moved to predetermined positions in both directions of operation of the switch.

9. In an electric switch, cooperating stationary and movable contacts, an operating bail connected to the movable contacts, an operating handle, a freely pivoted member, means on said handle providing a lost motion connection to said freely pivoted member, means providing a lost motion connection between said freely pivoted member and said operating bail, an overcenter spring operatively connected to said freely pivoted member, and means for effecting movement of the point of spring connection to the member independent of further movement of the operating handle when the spring has been moved to a predetermined position, said independent movement of the point of spring connection moving the spring through its dead center position and preventing maintenance of the parts in a semi-stable, dead center position.

10. In an electric switch, cooperating stationary and movable contacts, an operating bail connected to the movable contacts, an operating handle, a freely pivoted member, means on said handle providing a lost motion connection to said member, means providing a lost motion connection between said member and bail, a spring guide connected at one end of said member by a pin and slot connection, guide means for the opposite end of said spring guide, an overcenter spring mounted on said spring guide

and movable through its dead center position to effect snap movement of the operating bail and movable contacts, said slot being so related to the line of action of the overcenter spring as to effect movement of the pin within the slot to move the spring through its dead center position independent of movement of the member when the spring has been operated to a predetermined position.

11. In an electric switch, cooperating stationary and movable contacts, an operating bail connected to the movable contacts, an operating handle, a freely pivoted member, means on said handle providing a lost motion connection to said member, means providing a lost motion connection between said member and bail, a spring guide connected at one end of said member by a pin and slot connection, guide means for the opposite end of said spring guide, an overcenter spring mounted on said spring guide and movable through its dead center position to effect snap movement of the operating bail and movable contacts, said slot being in the form of an obtuse angle, the legs of said angle being so related to the line of action of the overcenter spring as to effect movement of the pin within the slot to move the spring through its dead center position independent of further movement of the member when the spring has been operated to predetermined positions in both directions of operation of the switch.

12. In an electric switch, cooperating stationary and movable contacts, operating means connected to the movable contacts, an operating handle, means interconnecting said handle and operating means, said interconnecting means including a lost motion connection to both handle and operating means, an overcenter spring operatively connected to said interconnecting means by a pin and slot connection and mov-

able through its dead center position to effect snap movement of the operating means and movable contacts, said slot having its defining edges inclined to the line of action of the overcenter spring when in what would normally be its dead center position, whereby the pin will move within the slot as the spring approaches its normal dead center position but prior to its arrival therein, movement of said pin within the slot effecting movement of the spring through its dead center position independently of movement of the operating handle whereby to prevent maintenance of the parts in a semi-stable dead center position.

13. In an electric switch, cooperating stationary and movable contacts, operating means connected to the movable contacts, an operating handle, means interconnecting said handle and said operating means, said interconnecting means including a lost motion connection to at least the operating handle, a spring guide connected to said interconnecting means by a pin and slot connection at one end, guide means slidably receiving the other end of said guide, an overcenter spring mounted on said spring guide and movable to its dead center position to effect snap movement of the operating means and the movable contacts, at least the edge of said slot against which the pin bears being inclined with respect to the line of action of the spring in its normal dead center position whereby said pin moves within the slot as the spring approaches its dead center position, this movement of the pin effecting movement of the spring through its dead center position independent of further movement of the operating handle when the spring has been moved to a predetermined position.

RALPH H. KINGDON.
